Primary Examiner — John R Yeh

(57) CLAIM

The ornamental design for a cleaning tool handle, as shown and described.

DESCRIPTION

FIG. 1 is a perspective view showing the new design for a cleaning tool handle;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines shown in FIGS. 1-7 depict portions of the cleaning tool handle that form no part of the claimed design.
